UNITED STATES PATENT OFFICE.

MILo C. HOARD, OF STRYKER, OHIO.

COMBINATION SAFE LOCK.

Application filed May 18, 1922. Serial No. 561,805.

To all whom it may concern:

Be it known that I, MILo C. HOARD, a citizen of the United States, and a resident of Stryker, in the county of Williams and

5 State of Ohio, have made an invention appertaining to a Combination Safe Lock; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 My invention has for its object to provide a combination lock for locking together any two members by positioning in a certain definite relation, a number of elements whereby engaging parts between the members may be placed in non-engaging relation 20 so that the members may be separated, and wherein the elements are so constructed and supported that they may be easily made and easily positioned to permit the disengagement 25 of the engaging members. The invention particularly has for its object to provide a combination lock for safes of different forms, such as ordinary standard safes having hinged doors, built-in safes, including 30 large bank safes, small wall or floor safes, and small safes that may be bolted to the floor or to walls or other fixed parts of a building or other structure, and which may be secured by means located within the 35 safe and extending through or into the supporting structure, and thus separation from the structure is prevented.

In embodiments of my invention any 40 number of sequential operations to set the combination may be used, and furthermore the number of sequential operations required may be readily reduced from the maximum number of operations. Thus the lock may be readily modified to change the 45 number of sequential operations required to unlock the lock. Further advantages and features of the invention will appear from the following description and upon an examination of the drawings forming a part 50 hereof.

The invention may be contained in locking devices of different forms, and usable for different purposes. To illustrate a practical application of the invention I have selected a structure containing the invention 55 as an example of such structures and shall

describe it hereinafter. The structure selected for purposes of illustration is shown in the accompanying drawings.

Figure 1 of the drawings illustrates a side view, partly in section, of the particular structure selected as an example of structures containing my invention. Fig. 2 is a sectional view of the lock taken on the broken line 2—2 indicated in Fig. 5. Fig. 3 is a view of the underside or bottom of the lock which, in the particular structure selected as an example, forms the head of the safe illustrated in Fig. 1. Fig. 4 is a sectional view of the head taken in a plane 70 located substantially at right angles to the section shown in Fig. 2. The section shown in Fig. 4 is taken on the line 4—4 indicated in Fig. 5. Fig. 5 is a top view of a part of the head, showing in section a sleeve that 75 interconnects the parts of the head, and also a section of a setting plunger. Fig. 6 illustrates the underside of the upper part of the head and also shows a section of the interconnecting sleeve and the setting plunger. Fig. 7 illustrates a sectional view taken on the line 8—8 indicated in Fig. 2. Fig. 8 is a sectional view taken on the line 8—8 also indicated in Fig. 2.

1 and 2, in Fig. 1, indicate the two members that are to be locked together by means of the lock involving my invention. In the form of construction selected as an example of embodiments of my invention 1 indicates the body of the safe. As shown, the safe 90 is in the form of a shell that may be located or built in a wall or floor or other fixed part of a structure, or may be secured by any means to any fixed object. Preferably the securing means extends into the shell 95 either through the bottom or through the side walls and so that the securing element or part, as the nut of a bolt or the head of a screw, is located within the shell, whereby accessibility to the securing means 100 to disconnect the shell from the fixed object may only be obtained when the head is unlocked and the shell is opened. In this way removal of the shell may be accomplished only by unlocking the head and 105 opening the shell.

2 is the other member that is locked to the shell 1 and in the form of construction shown it constitutes a flanged head that closes one end of the shell. The head 2 110 contains the locking element for locking the head to the shell. It is, of course, to

be understood that the locking elements may be located in a door or other member that is to be locked to the member 1. In the arrangements shown, the locking elements occupy a space about the size of the end of the shell and consequently the head that contains the locking elements forms not only the covering or closing means of the shell, but also constitutes the supporting frame of the locking elements. The head 2 is provided with a suitable flange that extends down around the end of the shell to completely cover the edge. In the form shown the edge of the shell that is covered and closed by the head is located in a horizontal plane so that the head forms a cover to the safe. The safe therefore may be provided with a flaring flange 3 that forms a base for the safe, and the safe may be supported by the flange 3, it being understood, however, that the axis of the safe may be located in any plane as may be desired.

In order to balance the weight of the head, particularly when the safe is located so that its axis extends vertically, a balancing spring 4 is so positioned as to counter-balance the weight of the head so that the head may be easily lifted, and be maintained in the position in which it is placed. In the form of construction shown the spring 4 is located in a sleeve 5 or in an opening 6 formed in the wall of the safe and between the lower end of the opening or bore 6 and a rod 7 that is connected to the head 2. When, therefore, the head 2 is raised to any point the upward pressure of the spring 4 against the lower end of the rod 7 will hold the head in the position that it may be placed. This may be done by merely using such force as is required to overcome any slight friction that may exist between the rod 7 and the surface of the hole or bore 6 and without lifting the weight of the head.

The rod 7 may be connected to the head by any suitable means. In the form shown the rod 6 is provided with a flange 8 at its upper end having bevelled side edges that fits into a channel 9 formed in an annular boss 10 extending around the edge of the lower side of the head. The rod 7 may thus be connected to the head by merely slipping the flange 8 into the channel 9 and thus the weight of the head will be counterbalanced by the spring 4 acting through the vertically disposed rod 7.

If the safe is so located that its axis is placed substantially in a horizontal plane, as for example, if the safe is located in or secured to a side wall of a building, the spring may be removed as the weight of the head will be supported by the flange of the head and the rod 7. In whatever position the safe may be located with reference to vertical or horizontal planes, the

rod 7 operates to so support the head that the flange of the cover or closing member may be readily swung into position to fit over the end of the safe. The rod 7 thus forms a pivotal member whereby the head may be readily supported when the safe is open and also whereby the head may be readily swung into open and closed positions.

The lock member 2 is formed of two parts. In the construction shown, one of the parts also forms the cover of the safe and, with reference to the combination lock, constitutes the setting means of the combination. The other part of the member 2 is stationary with reference to the rotatable setting part or means of the head and forms a support for the major controlling elements of the combination lock that are set by the setting part of the head. The part of the head containing the major controlling elements may also contain the engaging means that interengage the head or member 2 with the shell or member 1. In the form shown, the engaging means, namely, the bolts, that interlock the head with the shell are also supported in the supporting part of the head.

The setting part 11 of the head is a movable member and is rotatively connected to the supporting part of the head by means of the sleeve 12 and the spanner nut 14 that is threaded onto the end of the sleeve 12. The sleeve 12 has a head 13 that is suitably shouldered for engagement with the setting part 11 of the head and also with rotative elements that are located on the sleeve. The head 13 of the sleeve is located in a recess formed in a boss and forming with the boss a frustum-shaped projection extending from the top of the setting part of the head.

Within the sleeve 12 is located a controlling plunger 15. The plunger 15 is provided with a head 16 that is movable in a recess 17 formed in the head 13 of the sleeve 12. The plunger 15 is raised by a spring 18 located between the bottom of the bore formed in the sleeve 12 and the end of the plunger 15. The upward movement of the plunger 15 is limited by a pin 19 which is connected to the plunger 15 and moves in the slot 20 formed in the sleeve 12. Normally the pin 19 is located in the upper end of the slot 20 and so as to bring the head 16 of the plunger 15 substantially flush with the upper end of the sleeve 12. The pin 19 moreover, being located in the slot 20 of the sleeve 12, the plunger 15 rotates with the sleeve 12.

When the plunger 15 is in its uppermost position, that is, in its normal position, a recess 21 formed in the plunger 15 is located in alignment with a radially extending dog 22 located in an opening formed in the sleeve 12. The dog 22 is spring-pressed by a spring 23 that is located between a flange or shoulder formed on one end of the dog and the

bottom of the opening formed in the sleeve so as to yieldingly press the dog outward from the center of the sleeve. A toothed ring or ratchet 24 is located below the head 13 of the sleeve and in the setting part 11 of the head. The ratchet 24 is provided with a plurality of inwardly extending teeth that engage with the dog to move the dog inward when the setting part 11 of the head is rotated relative to the sleeve 12 in one direction, and to be engaged by the dog when rotated in the opposite direction. When, however, the plunger 15 is pushed down the recess 21 is moved below the dog 22 and inward movement of the dog 22 caused by the end of the dog passing over the teeth of the ratchet is prevented since the inner end of the dog 22 abuts against the plunger 15 and consequently the plunger 15 and the dog 22 become firmly connected to the ratchet 24 to prevent movement of these parts relative to the ratchet.

Rotation of the ratchet 24 relative to the setting part 11 is prevented by means of a pin 25 that is secured in the ratchet 24, and which may be located in any one of a number of holes 26 formed in the setting part 11 of the head. By this means the ratchet 24 may be adjustably located within the recess of the setting part 11. The ratchet 24 is provided with a part 27 that is flush with the inner edges of the teeth of the ratchet and forms what may be termed a smooth part in the path of the outer end of the dog 22. Adjustability of the ratchet by insertion of the pin 25 into any one of the holes 26 adjusts the smooth part 27 relative to the other parts of the locking device and affords one of the means for making up the combination for unlocking the lock. The ratchet therefore constitutes one of the coacting elements of the combination of the lock.

The supporting part 28 of the head is also provided with a ratchet 29 having inwardly extending teeth. A rotatable disc 30 is located within the ratchet 29 and is provided with a dog 31 that engages with the ratchet 29. The dog 31 may be an elastic metal strip that is secured to the disc 30 by any suitable means. It engages sequentially the teeth of the ratchet 29.

The ratchet 29 is provided with a pin 32 that may be inserted in any one of the number of holes 33 formed in the setting part 28 of the head. The ratchet 29 may thus be adjustably located with reference to the setting part 28 by placing the pin 32 in any one of the holes 33. The ratchet is provided with the part 34 having an inner surface that is located flush with the inner edges of the teeth of the ratchet, which may also be termed a smooth part of the ratchet. The adjustability of the ratchet 29 relative to the setting part 28 of the head has for its object to adjustably locate the smooth part 34 of the

ratchet relative to the head so that when the dog 31 is moved over the ratchet a clicking sound will be produced as it passes over the teeth of the ratchet, while a period of silence will be produced while the dog is passing over the smooth part of the ratchet. 70

The ratchet 29 is so disposed in the part 28 of the head that its teeth are placed in engaging relation to the dog 31 when the dog 31 is moved in a direction opposite to that in which teeth of the ratchet 24 will engage the dog 31. When, therefore, the setting part 11 of the head is rotated in one direction the dog 22 engages the ratchet 24 and causes rotation of the sleeve 12 and 80 the dog 31 moves over the ratchet 29, making a clicking sound as the dog passes the teeth of the ratchet, the supporting part of the head 28 remaining stationary relative to the setting part 11. When, however, the 85 setting part 11 is moved in the opposite direction the dog 22 moves over the teeth of the ratchet 24, producing a clicking sound, while the disc 30 is connected to the ratchet 29 through the dog 31 and consequently rotation of the disc 30 is prevented, 90

The disc 30 is provided with an eccentric boss or cam 35 that is surrounded by a ring 36. The ring 36 is pivotally connected to a part that is moved transverse the head by the movable member or setting part 11 of the head to engage locking elements or rings that are manipulated by movements also of the movable member or setting part 11 of the head to cause disengagement of 100 the elements or rings with the locking bolts.

The part or slide 37 is connected to the rings 36 by means of the pin 38. The slide 37 is located in a channel 39 formed in the setting part 11 of the head. When, therefore, the setting part 11 of the head is rotated in one direction and so that the dog 22 moves over the teeth 23 and the disc 30 is held in position by the dog 31 the eccentric boss or cam 35 operates to move the slide 37 in the channel 39 in a radial direction relative to the setting part 11 of the head. The slide 37 will therefore be located in different positions according to the angular movement of the setting part 11 of the head. 105

If the setting part 11 of the head is completely rotated the slide 37 will move across and back in its channel 39. The angular movement of the setting part of the head 11 relative to the supporting part 28 may be determined by counting the clicks that are produced by the dog 22 as it moves over the ratchet 24. For conveniently determining this angular relation between the two parts, the smooth part 27 of the ratchet 29 will be a determining starting point for measure and after a period of silence during continued movement of the setting part 11 of the head the first click will be the 110 first count and thereafter the setting part 115

120

125

130

135

of the head may be rotated to any point desired by merely counting the clicks produced after the period of silence. Thus the position of the slide may be determined by 5 the number of clicks that are produced by the dog 22 subsequent to the period of silence produced by the smooth part 27 of the ratchet 29.

The slide 37 is secured in position on the 10 setting part 11 by means of the disc 48 which is pressed onto the sleeve 12. The disc 30 is located between the sliding plate 37 and the disc 48. The sliding plate is also provided with a slot 49 through which the 15 sleeve 12 extends. Consequently the disc 30 and the sliding plate 37 are connected to the setting part 11 and the slide 37 rotates with the setting part 11, while rotation of the disc 30 and consequently of the cam part 35 20 is controlled by the dog 31 and is dependent upon the direction of rotation of the setting part 11.

The slide 37 may be provided with one or 25 more pins, such as the engaging pins 40 and 41. The supporting part of the head 28 is provided with a plurality of lock engaging elements or rings 42, 43 and 44 that also have engaging pins 45, 46 and 47. The rings 42, 43 and 44 are located in circular 30 channels formed in the supporting part and in which the rings are freely rotatable. The rings 42, 43 and 44 are each provided with a plurality of holes 50 into any of which bodies such as the pins 45, 46 and 47 may 35 be inserted. The pins may be thus adjustably located relative to the lock engaging elements. This constitutes three additional means of adjustment for making up combinations for unlocking the lock. The 40 adjustments of the pins 45, 46 and 47 may thus be permuted with the adjustments of the ratchets 24 and 29 to produce any one of a very large number of combinations. These 45 adjusting elements of the lock afford a remarkable range for selection of any combination whereby the safe may be opened. This range of selection is in the neighborhood of two million.

When the movable member or setting part 50 11 of the head has been rotated in one direction, and while the disc 30 is held by the dog 31 to move the part or slide 37, the pins on the slide are moved over the rings or elements that engage the locking means and 55 which are located in the supporting part 28. When, therefore, the setting part 11 has moved a certain angular distance the slide 37 has also been moved radially a certain distance. Movement of the slide is such 60 as to place one or the other of the pins located on the slide over one or the other of the rings so that upon subsequent rotation of the setting part 11 of the head, the pin of the slide located over that ring will engage 65 the pin of that ring and cause the ro-

tation of the ring with the setting part 11 of the head. The degree of movement of the part or slide 37 in order to place that particular pin over that particular ring is determined by the angular position of the 70 rack 24 relative to the rotative part 11, that is, the angular position of the smooth part 27 relative to the axis of rotation of the setting part 11. Setting of the rack 24 in different angular positions relative to the setting part 11 of the head changes the angular distance of movement requisite in order to bring that pin over that particular ring, and consequently more or less number of 75 clicks of the dog 22 is required in order to 80 bring that particular pin over that particular ring.

In the particular form shown, the pin 41 may be located over the ring 42 by counting twenty-nine clicks produced by the dog 22 upon left-hand rotation of the setting 85 part 11 because of the particular adjustment of the ratchet 24 in the setting part 11 of the head.

The setting part 11 of the head is now rotated in a right-hand direction since setting of the slide 37 is obtained by a left-hand rotation. Rotation to the right causes the pin that was set over any particular ring to engage the pin of that ring at some point in 90 the complete revolution of the setting part 95 of the head. In order to place the ring in a certain definite position in order that the engaging means between the members 1 and 2 may be disengaged the clicks that are 100 produced by the dog 31 are counted from the period of silence produced by the movement of the dog 31 over the smooth part 34 of the ratchet 29. The angular movement 105 of the setting part 11 of the head is then 110 determined by the position in which the smooth part 34 of the ratchet 29 is located relative to the supporting part 28 of the head. As the disc 30 is rotated by the head 115 it is connected to the sleeve 12 through the dog 22 and the pin 19 which is located in the slot 51 formed in the disc 30. Since 120 the disc 30 is rotated with the setting part 11, the slide 37 is not moved radially during the time that the ring caught by the slide 125 is moved by rotation of the setting part 11.

During the rotation of the setting part 11 to set the ring that is caught by the slide in its particular position the clicks produced by the dog 31 are counted, beginning with 130 the first count after the period of silence produced by the dog 31 moving over the smooth part 34. This places the ring in the desired position by means that are operated according to the adjustments of the ratchets 125 24 and 29.

The other rings are likewise placed in corresponding positions to permit movement of the means that interengage the members 1 and 2. The setting part 11 is again ro- 130

tated in such a direction as to again produce the clicking of the dog 22. The clicks are counted at once until a predetermined number is reached, when one of the pins of the 5 slide 37 will be placed above another of the rings located in the annular channels of the supporting part 28. Again reverse rotation of the setting part 11 will cause the clicking of the dog 31 and some where in a 10 complete revolution the engagement between the pin of the slide located above that particular ring and the pin of that particular ring takes place. When, therefore, the dog 31 reaches and passes over the smooth portion 15 of the ratchet 29 the clicks may be counted, and thus the ring may be placed also in such a position that will release the engaging means between the members 1 and 2 when the predetermined number of clicks have 20 been produced, as for example, the pin 40 will be placed over the ring 43 when the setting part of the head has been rotated to the left so as to produce seven clicks. It is then rotated to the right one complete revolution in order that the pin 40 may pick up 25 the pin of the ring 43 and then after the period of silence the clicks produced by the dog 31 are counted. When, therefore, twenty-two clicks have been made the ring 30 43 is placed in position such that the engaging means will be released also from this ring.

The remaining ring 44 is also placed in position to release the engaging means by 35 the same process. The setting part 11 is rotated counter-clock-wise a certain number according to the position of the pins on the slide 37. The pin 41 in the form shown may now be placed in position for engaging the 40 pin of the ring 44. This is obtained by counting the clicks that are produced by the dog 22 in the counter-clockwise movement. In the particular setting of the parts shown, the pin 41 is placed over the ring 44 by 45 counter-clockwise movement and upon three clicks of the dog 22. The setting part 11 is now rotated clockwise one complete revolution, which will cause the dog 41 to pick up the pin of the ring 44 and after the period of 50 silence caused by the dog 31 moving over the smooth part 34 of the ratchet 29 and upon the production of forty-three clicks caused by the dog 31 the ring 44 will be placed in position for release of the 55 engaging means between the members 1 and 2.

It will thus be seen that changes of the 60 number of clicks required to position the slide 37 may be obtained by changing the position of the ratchet 24 and the setting of the rings may be altered by changing the position of the pins in the rings and changing of the position of the ratchet 29, which gives an exceedingly large number of combinations, any one of which may be used to

place the rings in position to release the engaging means between the members 1 and 2.

In order that the setting part 11 may be placed in juxtaposition to the supporting part 28, annular channels 68 may be formed 70 in the setting part 11 in which the pins 45, 46 and 47 are located.

The rings being now so placed that the engaging means is released, it may now be 75 withdrawn and the two parts may be unlocked. This may be accomplished by merely drawing one or more bolts that are released by the rings, as by a hand lever or by any other means. In the form of the invention shown it is accomplished by the 80 rotation of the setting part 11 of the head.

In order to prevent the pins of the slide, that has set the rings in their positions of release of the locking means, from disturbing the rings, the slide is moved by left-hand rotation of the head 11 a short distance, which will so place the pins of the slides such that they will not engage with the pins of the rings. Counter-clockwise 85 movement that produces three or four clicks in the dog 22 will thus position the slide so that the rings will not be disturbed.

When the pins of the slide are placed in position to clear the pins of the rings, the locking means may be operated to unlock 90 the members 1 and 2. In order to operate the locking means the head 11 is rotated clockwise until the plunger 15 can be pressed down against the spring 18, that is, until the pin 52 registers with the slot 53, whereupon 95 the pin 52 may pass below the inwardly extending flange 54, and rotation of the head 11 while the plunger 15 is being held down will place the pin 52 under the flange 54, which will hold the pin 15 down. This also 100 places the pin 52 in the slot 55 which is located in a channelled ring 56. Rotation of the head 11 after the pin 52 enters the slot 55 causes rotation of the ring 56.

The channel 57 of the ring 56 is so formed 110 as to produce a double cam 58 against which the inner ends of the locking bolts 59 are pressed by the springs 60. The springs 60 press against pins 69 that are secured to the bolts 59. The pins protrude into openings 115 70 formed in the supporting part 28 of the head. The inner ends of the bolts 59 fit in the channel 57 and thus rotation of the bolts 59 is prevented. When the plunger 15 is pressed down the recess 21 is moved below 120 the inner end of the dog 22 and consequently there can be no endwise movement of the dog 22 since its inner end abuts against the plunger 15. This locks the sleeve 12 to the setting part 11 of the head. Also movement 125 of the pin 52 through the slot 53 disconnects the plunger 15 from the disc 30 and thus connects the setting part 11 of the head directly to the double cam formed by the channel 57.

After engagement has thus been established between the double cam 58 and the setting part 11 rotation of the setting part will cause rotation of the double cam and the springs 60 will move the locking bolts 59 inward as the shorter radii of parts of the cam are brought in alignment with the axis of the bolts. The movement of the double cam 58 is limited by the pins 64 and 71 which engage an end of one or the other of the bolts 59. One pin 71 engages the end of one bolt when the bolts are in unlocking position and the pin 64 engages the end of the other bolt 59 when the bolts are in locking position. The ends of the bolts 59 when in locking position enter holes 61 formed in the member 1, that is, in the shell or wall or fixed part of the safe. When, however, the double cam has been rotated sufficiently the locking bolts 59 are drawn from the holes 61 and the members 1 and 2 are unlocked and the member containing the head may be moved from the other member, that is, the safe may be opened.

In order to release the bolts so that they can be withdrawn from the holes the rings 42, 43 and 44 are provided with notches 62 that conform to the shape of the bolt and the bolts are provided with notches 63 that conform to the shape of the rings where the surfaces of the bolts and the rings intersect, so that when the bolts are in locking position the rings may be freely moved in the recesses 63 and when the rings are in position of release of the bolts the bolts may be freely moved in the recesses 62. When the rings and the bolts are thus placed in this definite relation to each other the safe may be readily locked and unlocked, but unless all of the rings are in such a position that the surfaces of the recesses coincide with the surfaces of the rings of the bolts the bolts cannot be withdrawn from their locking positions. Furthermore, when the bolts are in unlocking positions the rings cannot be moved because of the engagement between the surfaces of the recesses of the rings and the surfaces of the bolts. Consequently, when the bolts are in this position the rings cannot be moved, which will therefore obviate the necessity of going through the sequential operations in order to lock the safe.

If it is desired to temporarily secure the members 1 and 2 together it may be done by merely rotating the setting part 11 in a direction to cause the bolts 59 to enter the holes 61. This will place the pin 52 in line with the slot 53, which will permit the plunger 15 to rise. The setting part 11 may then be rotated to the right as much as may be desired. If it is desired to then open the safe, all that is necessary is to rotate the setting part 11 to the right until the pin 52 enters the slot 53 and also enters the slot 55

and engages the cam ring 56. This will cause rotation of the cam ring and permit the locking bolts to be pressed inward by the springs 60, which will unlock the safe.

In order to permanently lock the safe the cam ring 56 is rotated until its rotation is stopped by the pin 64, which will force the bolts 59 into the holes 61 and at the same time the pin 52 will be forced upward from the slot 55 through the slot 53 and enter the space 65. At the same time the pin 19 enters the slot 51 in the disc 30, which establishes connection between the sleeve 12 and the disc 30. Also the recess 21 is placed in alignment with the dog 22 to permit free endwise movement of the dog 22 except as it is yieldingly pressed by the spring 23. Counter-clockwise rotation of the head 11 will cause movement of the slide 37 and cause one of the pins of the slide 37 to engage one or more of the pins of the rings 42, 43 and 44 and thus cause the rings whose pins are thus engaged to move through one or more of the slots 63 of the bolts 59 and thus secure the bolts in their locking positions.

In order to unlock the members 1 and 2 the sequential operations heretofore described must necessarily be performed. It is preferable to locate the bolts 59 in radii that form an angle slightly greater or less than 180° for the reason that if they were in diametrically opposite positions the recesses of the rings could otherwise be placed in any one of two positions in order to enable the bolts to be withdrawn from locking position. By locating the bolts at an angle other than 180° the rings must be placed in the definite position described in order that the bolts may be withdrawn.

To briefly describe the locking device illustrated in the drawings, and which has been selected as an example of embodiments of my invention, the setting part of the head 11 is rotated in one direction, as for example, counter-clockwise to a certain angular position as is predetermined by the position of the ratchet 24, which position is indicated by the production of a certain number of clicks by the dog 22 after it has passed over the smooth portion 27 of the ratchet, that is, after it has passed through the period of silence produced by the smooth portion 27. This also causes the same rotation of the disc 30 which moves the slide by reason of the connection of the slide to the cam of the disc through the eccentric ring. The slide is so positioned that one or other of its pins is placed over one of the rings located in the supporting part 28 of the head. Reverse rotation of the setting part 11 causes the pin of the slide that has been placed over the particular ring to engage with the pin of the ring. When the setting part 11 has been rotated one complete rota-

tion it has engaged, at some point in the rotation, the pin of the ring. The setting part 11 is then rotated through the silent period produced by the smooth portion of 5 the ratchet 29. The rotation is continued until the ring has been placed in a definite position which is predetermined by the setting of the pin of the ring and the setting of the ratchet 29. This predetermined position 10 is defined by the number of clicks that are produced by the dog 31 after it passes the smooth part of the ratchet 29. This places the ring in position such that it releases the locking bolts 59. The setting part 15 11 is now rotated counter-clockwise and the clicks produced by the dog 22 are counted, which places one or the other of the pins of the slide in a definite position, that is, in position to engage the pin of another ring 20 when the setting part 11 is rotated clockwise. This position is also determined by the number of clicks produced by the dog 22. The setting part 11 is again rotated clockwise one complete rotation so as to 25 cause the pin of the slide to engage the pin of the ring. Continued movement after one complete revolution brings the dog 31 over the smooth part of the ratchet 29. Continued rotation counting the clicks produced 30 by the dog 31 determines the angular position of the ring that has been caught up and is being moved by rotation of the setting part 11 of the head. This predetermined position that will produce release of the 35 bolts 59 is determined by the number of counts, which may be established by setting the pin of the ring in any one of the holes of the ring. The setting part 11 is again rotated counter-clockwise, the angular position being determined by the number of 40 clicks produced by the dog 22, which again defines the position of one of the pins of the slide and when the required number of clicks have been produced the pin is positioned 45 over the remaining ring, if there are but three rings, it being understood that any number of rings may be used in the combination. The setting part 11 of the head is again rotated one complete revolution so 50 as to make certain that the pin of the ring has been caught by the pin of the slide and after the dog 31 passes through the period of silence the clicks produced by the dog 31 are counted and when the predetermined 55 number of clicks have been produced, which will be according to the location of the pin of that ring relative to the recesses or notches formed in the ring. This ring will then also be placed in the position of release of the bolt 59. The rings having now been 60 placed so that the recesses 62 and 63 of the rings and the bolts register with one another, the bolts may be withdrawn from the holes 61. This may be accomplished by any suitable means. In the form shown, the setting 65 part 11 is rotated clockwise while the plunger 15 is pressed down so as to cause the pin 52 to engage with the double cam of the ring 56, whereupon further movement will cause the springs 60 to move the bolts 70 59 inward and out of the holes 61 as the shorter radii of the double cam are placed in alignment with the axis of the bolts. The safe is now unlocked and the head may be easily lifted by reason of the counter- 75 balancing spring 4. If it is desired to reduce the number of operations required to unlock the combination it may be done by securing one of the rings permanently in position such that it will be maintained in 80 position of release of the bolt. This may be accomplished in any suitable way. In the form of the invention shown, openings 66 may be formed in the supporting part 28 of the head and one or more of the 85 rings may be tapped at points that are in alignment with the openings 66 when the recesses 62 of the rings are in position to release the bolts 59, such as at the point 67. Threaded pins may be screwed into the 90 tapped opening 67 in order to secure one or more of the rings in position. This will obviate the necessity of making the necessary counts to cause engagement of the pin of the slide with the pin of that particular 95 ring, and also to step the ring around to the required position.

I claim:—

1. In a combination lock, a locking means, a rotatable member, a part rotated and moved relative to the rotatable member by the rotatable member, one or more elements for engaging the locking means and engaged and operated by the said part. 100
2. In a combination lock, a locking means, a rotatable member, a part moved relative to the rotatable member by the rotatable member when the rotatable member is rotated in one direction, and rotated with the rotatable member when the rotatable member is rotated in the opposite direction, one or more elements for engaging the locking means and operated by the said part to place the elements in disengaging relation to the locking means. 110
3. In a combination lock, a locking means, a rotatable member, a part moved relative to the rotatable member by the rotatable member when the rotatable member is rotated in one direction, and rotated with the rotatable member when the rotatable member is rotated in the opposite direction, one or more elements for engaging the locking means and operated by the said part when the rotatable member is moved in the said other direction to place the elements in disengaging relation to the locking means. 120
4. In a combination lock, a locking means, a rotatable member, a part movable transverse to the rotatable member by the rotat- 125
- 66

- able member when the rotatable member is rotated in one direction, and rotated by the rotatable member when the rotatable member is rotated in the other direction, a plurality of elements for engaging the locking means and operated by the said part when the rotatable member is rotated in the said other direction to place the elements in disengaging relation to the locking means.
10. 5. In a combination lock, a locking means, a movable member, a part moved relative to the movable member when the movable member is moved in one direction, and moved with the movable member when the movable member is moved in the other direction, one or more elements for engaging the locking means and operated by the said part when moved in the said other direction to disengage the elements from the locking means.
15. 6. In a combination lock, a locking means, a movable member, a part movable in two directions by the movable member, a plurality of elements for engaging the locking means and engaged by the said part when moved in one direction, and moved by the part to disengage the locking means when moved in another direction.
20. 7. In a combination lock, a locking means, a movable member, one or more elements for engaging the locking means, and having bodies adjustably located relative to the said elements, a part moved by the movable member into position to engage the bodies when the part is moved in one direction and to engage and move the elements when the part is moved in another direction to disengage the elements from the locking means.
25. 8. In a combination lock, a locking means, one or more elements for engaging the locking means, a part movable in two directions for engaging the elements when moved predetermined distances in one direction, and for moving the elements to disengage the locking means when moved predetermined distances in the other direction, and an adjustable means for indicating the distances moved in the said directions by the said part.
30. 9. In a combination lock, a locking means, one or more elements for engaging the locking means, a rotatable member, a part moved by the said rotatable member in two directions for engaging the elements when moved predetermined distances in one direction, and for moving the elements to disengage the locking means when moved predetermined distances in the other direction, an adjustable means for indicating the distances moved by the said part in one direction, and a second adjustable means for indicating the distances moved by the part in the other direction.
35. 10. In a combination lock, a locking means, a rotatable member for operating the locking means, one or more elements for engaging the locking means to prevent the operation of the locking means, the elements having adjustable bodies, a movable part operated by the rotatable member for engaging the adjustable bodies when the movable part is moved predetermined distances, and for moving the elements to disengage the locking means when moved predetermined distances after engaging the bodies.
40. 11. In a combination lock, a locking means, a rotatable member for operating the locking means, one or more elements for engaging the locking means to prevent the operation of the locking means, the elements having adjustable bodies, a movable part operated by the rotatable member for engaging the adjustable bodies when the movable part is moved predetermined distances, and for moving the elements to disengage the locking means when moved predetermined distances after engaging the bodies, means for indicating the distance moved by the movable part to engage the bodies, and means for indicating the distances moved by the elements to disengage the locking means.
45. 12. In a combination lock, a locking means, a rotatable setting member, a slide movable across the setting member and moved crosswise by the setting member when the setting member is moved in one direction, one or more elements for engaging the locking means and engaged by the slide when moved a predetermined distance across the setting member and operated by the said setting member when moved in the opposite direction to disengage the elements from the locking means.
50. 13. In a combination lock, a locking means, a rotatable setting member, a slide movable across the setting member and moved crosswise by the setting member when the setting member is moved in one direction, a plurality of rings for engaging the locking means and engaged by the slide when moved a predetermined distance across the setting member and operated by the said setting member when moved in the opposite direction to disengage the rings.
55. In testimony whereof I have hereunto signed my name to this specification.
- MILO C. HOARD.
